HUMIDIFIER

Francis A. Furlong, River Forest, Ill., assignor to
Autogas Company, Chicago, Ill., a corporation
of Illinois

Application July 14, 1941, Serial No. 492,287

7 Claims. (Cl. 126—113)

This invention relates to humidifiers and more particularly to devices for regulating the humidity of living spaces in rooms or the like.

One of the objects of the invention is to provide a humidifier for use with a heating plant having a duct for conducting heated air to the space in which operation of the humidifier is controlled in accordance with the temperature of the duct. This insures that humidity will be discharged into the duct at a time when there is a flow of heated air therethrough, so that the humidity will be carried properly throughout the living space, and so that condensation of water in the duct will be prevented.

The above and other objects and advantages of the invention will be apparent from the following description when read in connection with the accompanying drawings, in which:

Figure 1 is a diagrammatic view with parts in section of a heating plant installation including a humidifier embodying the present invention;

Figure 2 is an enlarged elevation of the control valve of Figure 1;

Figure 3 is a diagrammatic section of the control valve; and

Figure 4 is an enlarged section of the humidifier with the casing removed.

The humidifier itself is of the same general type as those more particularly described and claimed in the co-pending applications of Furlong and Penfold, Serial No. 319,228, filed February 16, 1940, and Serial No. 356,270, filed September 11, 1940. As shown in Figure 4, the humidifier comprises a tank having an enlarged upper portion 10 and a reduced lower portion 12, connected by a horizontal wall 14, and adapted to contain water above the wall 14 substantially at the level shown. Water in the tank is heated by heating means shown as comprising a gas burner 16, insulated from the reduced portion 12 of the tank and discharging heated vapor against the horizontal wall 14. A heating jacket 18 conducts the vapor around one side of the tank to a flue pipe 20. Gas is supplied to the burner 16 through a pipe 22 controlled by a manual shut-off valve 24, and by a safety valve 26, normally urged closed by a spring and held open by a bimetal strip 28 responsive to the heat of the burner. When the burner is in operation, the strip 28 will be deflected to open the valve 26, but if the burner should accidentally be extinguished, the strip 28 will cool, allowing the valve 26 to close.

Water is admitted to the tank through a pipe 30 discharging into a stand pipe 32 arranged beside the tank and communicating therewith at the bottom of the reduced lower portion 12. Out-

let of water from the pipe 30 is controlled by a bi-metal strip 34 which, when cooled, closes the end of the pipe 30. In order to heat the strip 34, an angle section of pipe 36 is extended from the stand pipe 32 into the tank and terminates in a downwardly facing end substantially at the desired water level. When the water drops below the open end of the pipe 36, vapor from the tank will flow through this pipe to heat the strip 34, thereby admitting additional water to the tank to raise the level sufficiently to close the end of the pipe 36.

According to one feature of the present invention, flow of vapor through the pipe 36 when the water level is below the open end thereof is insured by maintaining a predetermined minimum vapor pressure in the tank. For this purpose, the tank is provided with a vapor outlet 38 extending upwardly from the upper end thereof and having a weighted disc 40 held in place by guides 42, normally seated on the upper end of the outlet pipe 38. If the pressure in the tank is below the value predetermined by the weight and size of the disc 40, this disc will remain closed and all vapor generated will flow out through the pipe 36. As the vapor pressure increases, the disc 40 will be unseated to allow the flow of vapor through the outlet 38.

In order to prevent the accumulation of scale or slime in the tank such as to prevent or interfere with proper operation, the tank is adapted to be drained periodically. This may be accomplished by means of a manually operated valve 44 connected to the lower end of the stand pipe 32, but is preferably carried out automatically at predetermined time intervals by an ejector 46 communicating with the stand pipe 32 and the lower tank portion 12. The ejector discharges into a drain pipe 48 extending above the level of water in the tank a sufficient distance to prevent accidental overflow so that water will flow therethrough only when the ejector is operated. The ejector receives water through a conduit 50 which communicates also with a spray nozzle 52 arranged in the upper part of the tank. A restricted orifice 54 limits the quantity of water flowing to the spray nozzle and insures an adequate supply of water to operate the ejector. The supply of water to the spray nozzle and the ejector is controlled by a valve 56 operated by an electric motor 58. The motor 58 is preferably energized periodically for a predetermined time interval by a clock mechanism 60 controlling the circuit through a mercury switch 62, which energizes the motor 58. In this way, the valve 56

is opened periodically to withdraw water from the tank by operation of the injector and at the same time to wash out the tank by operation of the spray mechanism 52.

It will be noted that when the valve 50 is opened and the ejector is operating, the water level will be reduced below the open end of the pipe 36. At the same time, however, the spray mechanism is spraying cold water into the tank so as to prevent the formation of vapor therein, thereby preventing opening of the thermostatic valve 34. To insure a minimum supply of water in the tank for starting of the water supply mechanism after a flushing and draining operation, a wall 64 is provided adjacent one end of the horizontal bottom 14 to hold a minimum supply of water thereon.

Figure 1 illustrates the installation of a humidifier of the type just described in connection with a warm air furnace, including a fire pot 66 with a warm air furnace, including a fire pot 66 discharging through a flue 68 and surrounded by a jacket 70. A cold air return duct 72 supplies air to the lower portion of the jacket and warm air flows from the upper end of the jacket through ducts 74 communicating with registers 76 in the floor 78 of the space to be heated. While one conventional type of warm air furnace has been illustrated, it will be understood that the invention can be applied to warm air furnaces of any desired type.

The humidifier mechanism is enclosed in a casing 80 arranged adjacent the furnace and communicating through a conduit 82 with one of the ducts 74. The casing is provided with a series of louvres or openings 84 to provide for the admission of air thereto, the air being heated in its flow around the tank and mixing with vapor discharged from the outlet 82, the mixture of air and vapor flowing through the conduit 82 into the duct.

Water is supplied to the humidifier from any suitable source, such as the usual city water mains, through a pipe 86, and gas is supplied to the burner 16 through a pipe 88, the supply of gas to the burner 16 being controlled by a valve mechanism, indicated generally at 90, mounted on the duct 74 so as to be responsive to the temperature thereof. The valve mechanism 90, as best seen in Figures 2 and 3, comprises a body formed with an inlet passage 92 and an outlet passage 94, having a valve 96 arranged therebetween and normally seated by a spring 98. The valve has a stem projecting downwardly therethrough into the open lower portion of the casing on which the casing fits over the duct, and resting on one end of a lever 100 adjustably supported at its opposite end on a screw 102. By adjusting the screw 102, the initial seating of the valve may be changed so as to make it responsive to different temperatures.

The valve is controlled by a bi-metal strip 104, rigidly supported at one end in the casing and at its opposite end engaging an enlarged portion 106 on the lever 100. As the strip 104 is heated, it deflects upwardly, as seen in Figure 3, to open the valve. When the valve is closed, a predetermined minimum amount of fuel is by-passed through an adjustable by-pass 108 to maintain the burner in a low stage of operation.

In use, with the apparatus installed as shown, when the furnace is operating and the temperature of the duct is above that for which the valve is adjusted, the valve 96 will be opened to admit a maximum supply of fuel to the burner 16. At this time, the water in the tank will be

vaporized rapidly and will be supplied to the living space through the conduit 82 and the duct 74. When the furnace is out of operation or operating at a very low rate, such that the duct 74 is cooled below the temperature for which the valve is set, the strip 104 deflects downwardly, permitting the valve 96 to close, so that only a minimum quantity of fuel flowing through the by-pass 108 will be supplied to the burner. This will operate the burner at a low rate such as to maintain the water heated substantially to the boiling point without causing any material discharge of vapor through the conduit 82. Thus vapor is supplied only at times when an adequate supply of warm air is flowing through the duct 74 to carry the vapor properly into the room and when the duct is sufficiently warm to prevent condensation of vapor therein.

While one embodiment of the invention has been illustrated and described in detail, it will be understood that this is illustrative only and is not to be taken as a definition of the scope of the invention, reference being had for this purpose to the appended claims.

What is claimed is:

1. In combination, a heating plant including means for heating air and a duct for conducting heated air to a space to be heated, a humidifier comprising a casing, means in the casing to vaporize water, a conduit for conducting the vaporized water to said duct, means to supply operating power to said vaporizing means, and control means for said supply means responsive to the temperature in said duct to reduce the supply of operating power to the vaporizing means when the temperature in said duct is below a predetermined degree.

2. In combination, a heating plant including means for heating air and a duct for conducting heated air to a space to be heated, a humidifier comprising a casing, a tank in said casing adapted to contain water, heating means in the casing to heat said tank thereby to vaporize water therein, a conduit for conducting the vaporized water to said duct, means for supplying heat energy to said heating means, and control means for the supplying means responsive to the temperature in said duct to reduce the supply of heat energy when the duct is below a predetermined temperature.

3. In combination, a heating plant including means for heating air and a duct for conducting heated air to a space to be heated, a humidifier comprising a casing, a tank in said casing adapted to contain water, a fluid fuel burner in the casing to heat said tank, thereby to vaporize the water therein, a conduit for conducting the vaporized water to said duct, a conduit for supplying fluid fuel to said burner, a valve in said fuel conduit, and a thermostat responsive to the temperature of said duct to control said valve.

4. In combination, a heating plant including means for heating air and a duct for conducting heated air to a space to be heated, a humidifier comprising a casing, a tank in said casing adapted to contain water, a fluid fuel burner in the casing to heat said tank thereby to vaporize the water therein, a conduit for conducting the vaporized water to said duct, a conduit for supplying fluid fuel to said burner, a valve in said fuel conduit, means forming a restricted by-pass around the valve to provide a minimum fuel supply to the burner, and a thermostat responsive to the temperature of the duct to close the valve when the temperature falls below a predetermined

mined minimum and to open the valve when the temperature exceeds said minimum.

5. In combination, a heating plant including means for heating air and a duct for conducting heated air to a space to be heated, a humidifier comprising a casing, a tank in said casing adapted to contain water, heating means in the casing to heat the tank to vaporize water therein, said casing having an air inlet opening therein to admit air to mix with the vaporized water, a conduit for conducting the mixture of air and water vapor to the duct, means for supplying heat energy to the heating means, and control means responsive to the duct temperature to control said last named means.

6. In combination, a heating plant including means for heating air and a duct for conducting heated air to a space to be heated, a humidifier comprising a casing, a tank in said casing adapted to contain water, a heater in the casing to heat the tank to vaporize water therein, a pipe in the tank to conduct vapor therefrom when the water therein falls below a predetermined

level, means controlled by flow of vapor through said pipe to control admission of water to the tank, said tank having a vapor outlet in its upper portion, a conduit to conduct vapor from said outlet to the duct, means for supplying heat energy to said heating means, and control means responsive to the duct temperature to control said last named means.

7. In combination with a heating system including a heating unit for heating air, a duct for conducting heated air from the unit to a space to be heated and a return duct for conducting air from the space to the unit, a humidifier comprising a tank adapted to contain water, means to heat the water in the tank to vaporize it, a conduit to conduct the vapor to one of the ducts to mix with air flowing therethrough, and control means for the heating means responsive to the temperature of the air in the first named duct to decrease the heat supply when the air temperature falls below a predetermined minimum.
